UNITED STATES PATENT OFFICE.

E. EUGENE SARGEANT, OF NEWARK, NEW JERSEY.

BRIDLE-BIT.

SPECIFICATION forming part of Letters Patent No. 289,452, dated December 4, 1883.

Application filed September 25, 1883. (No model.)

To all whom it may concern:

Be it known that I, E. EUGENE SARGEANT, of Newark, in the county of Essex and State of New Jersey, have invented Improvements 5 in the Construction of Bridle-Bits; and I do hereby declare the following to be a full and exact description thereof, reference being had to the accompanying drawings, making part of this specification—

10 Figure 1 being a top view of a bit constructed with my improvements; Fig. 2, a front view of the same; and Figs. 3, 4, and 5, views in detail, showing my improved mode of constructing the parts of a jointed mouth- 15 piece.

Like letters designate corresponding parts in all of the figures.

In the construction of jointed mouth-pieces of malleable cast metal, I have made an 20 improvement in means for linking together the two eyes *b c* of the joint, as follows: The open eye *b* is cast with a core, so as to leave an opening of sufficient width to admit the close eye *c* between lapped parts *d d*, substantially as shown in Figs. 3 and 5. These lap parts have ends of square form or slightly inclined form outwardly, as shown, and the corresponding shoulders, *e e*, against which the ends are to fit, are of corresponding form—that 25 is, square or slightly undercut—so that when the two lap parts are swaged or pressed together a close joint will be made, and one not

liable to become opened or started in the slightest degree. Besides, to obtain the best results, I make little protuberances or ridges 35 *ff* on the outer edges at the ends of the lapped parts, as shown in Figs. 3, 4, and 5. Then, when the parts are pressed together, these ridges are swaged down or “spilled” over the adjacent seams, thereby filling the seams 40 and making a better job than would otherwise be possible for making a smooth and unbroken surface. This joint is a strong and excellent one, cheaply made, and produces a superior bit. This means of making an open 45 eye to receive another part and closing the eye is applicable to any part of a bit or mounting as well as to a jointed mouth-piece.

I claim as my invention—

1. In a bridle-bit, the eye *b* of a jointed 50 mouth-piece, cast with open lapped parts *d d*, each adapted to fit against a shoulder on the opposite part, substantially as and for the purpose herein specified.

2. A bridle-bit provided with an eye cast 55 with lapped parts *d d* and protuberances *f f* thereon, substantially as and for the purpose herein specified.

In testimony whereof I have signed my name in the presence of two witnesses.

E. EUGENE SARGEANT.
